UNITED STATES PATENT OFFICE.

HERBERT C. SHAW, OF CHICAGO, ILLINOIS, ASSIGNOR TO BAUER & BLACK, OF CHICAGO, ILLINOIS, A CORPORATION OF ILLINOIS.

SUSPENSORY SACK OR POUCH.

No. 913,855.

Specification of Letters Patent.

Patented March 2, 1909.

Application filed March 7, 1907. Serial No. 361,084.

To all whom it may concern:

Be it known that I, HERBERT C. SHAW, a citizen of the United States, residing at Chicago, in the county of Cook and State of Illinois, have invented new and useful Improvements in Suspensory Sacks or Pouches, of which the following is a specification.

This invention relates to improvements in suspensories and has reference more particularly to the sack or pouch to receive the testicles.

In the manufacture of sacks or pouches for suspensory bandages heretofore a string or cord has been inclosed within a binding sewed 15 to one edge of the fabric, which string or cord has been utilized to form the penis opening. This is illustrated in Reissue Patent No. 11,369 dated Oct. 3, 1893.

The object of my invention is to simplify 20 and improve the manufacture of sacks or pouches for suspensories, to lessen the cost of manufacture, to dispense with the binding around the edge of the penis opening and to make the edge of said opening more yielding 25 and more comfortable to the wearer.

In the accompanying drawings illustrating 30 the invention Figure 1 shows the fabric piece ready to be folded. Fig. 2 shows the piece folded. Fig. 3 shows the piece gathered at the top and ready to receive the bands. Fig. 4 shows the completed suspensory. Fig. 5 is an enlarged transverse sectional view through the edge of the penis opening. Fig. 6 is a detail enlarged view of the edge of the 35 penis opening.

In practicing my invention I provide a piece 7 of knitted fabric of the proper size for forming the sack or pouch, in one selvage edge 8 of which piece one or more elastic 40 cords 9 are inclosed by the stitching 10 (Fig. 5) during the knitting operation. In the drawings I have shown three elastic cords located side by side in parallel relation but it will be understood that I may use one cord 45 at the extreme edge or a plurality of cords, as shown, as may be desired. The piece 7 may be knitted separately but in general practice a long strip of the fabric will be knitted from which the pieces are cut as required. Each piece when spread out smoothly 50 and evenly is rectangular in shape but the elastic cords will gather up or draw one selvage edge of the piece, as shown in Fig. 1, so

that when the piece is folded upon itself, as shown in Fig. 2, the penis opening will be 55 formed by the gathered or drawn edge of the piece. The folded piece is then gathered at the top, its elastic edges overlapped at S' and then sewed transversely, with a row of stitching 11 to form a neck 12 and complete the 60 sack or pouch 13 as clearly shown in Fig. 4.

The suspensory is completed by sewing the binding 14 on the upper edge of the neck and attaching the waist band 15 and the leg bands 16. The sack or pouch is held in 65 shape at the top of the penis opening, and the elastic edges are fastened together to form said opening, by the stitching 11, and the binding 14 finishes the sack or pouch and holds the upper edge of the neck 12 in 70 shape. The stitching 11 and binding 14 secure the elastic cords so that the latter will only stretch under strain and not pull loose. The elastic cords, therefore, maintain the penis opening in approximately 75 circular shape of a predetermined size, but at the same time permit the edges of the opening to yield and thereby fit the opening to the penis.

It will be observed that the elastic cords 80 are incorporated directly in the piece of fabric forming the sack or pouch by inclosing them within the stitches (Figs. 5, 6) during the knitting operation, and thus I dispense entirely with the necessity of fastening the 85 cord or cords to the piece of fabric by a binding along the selvage edge containing the cords and in a separate operation. The binding heretofore employed necessarily limits the enlargement of the penis opening but 90 with my invention the enlargement of the penis opening is limited only by the elasticity of the cords and the capability of the selvage edge of the fabric in which the cords are incorporated to stretch. Furthermore the 95 edge of the penis opening as provided by my invention is smooth and soft and will be more comfortable to the wearer than if the edge were bound in the manner heretofore employed, as illustrated in the patent above 100 mentioned. By incorporating the elastic cords in the fabric itself while the latter is being knitted I not only dispense with the separate operation of applying the cords and binding to the piece but it will be observed 105 that the elastic cords naturally gather or

draw up the edge of the piece into proper form for the penis opening.

My invention is simple in character and it greatly facilitates and lessens the cost of manufacture and at the same time produces a sack or pouch having a penis opening which will readily adjust itself to fit the penis without chafing or otherwise proving uncomfortable to the wearer.

10 What I claim and desire to secure by Letters Patent is:

1. A suspensory sack or pouch composed of a single piece of knitted fabric having one or more elastic cords knitted therein lengthwise of the piece at one selvage edge and wholly inclosed within the stitches, said piece being gathered transversely adjacent to its ends and said ends being stitched transversely and the elastic edges at said gathered parts being connected to provide 20 a penis opening, the edge of which is formed

by the selvage edge of the fabric containing said elastic cords.

2. A suspensory sack or pouch composed of a single piece of knitted fabric having one or more elastic cords knitted therein lengthwise of the piece at one selvage edge and wholly inclosed within the stitches, said piece being gathered transversely adjacent to its ends and the elastic edges of said 30 gathered parts overlapped, a row of stitching transversely across the gathered parts of said fabric to form a neck for the pouch above said stitching and a penis opening below said stitching, the edge of said opening 35 being formed by the selvage edge of the fabric containing the elastic cords, and a binding at the ends of the fabric.

HERBERT C. SHAW.
